DESIGN FOR A CHILD'S FEEDING SET

Rolf J. Falk, Zanesville, Ohio, assignor to Shawnee Pottery Company, Zanesville, Ohio, a corporation of Ohio

Application April 30, 1946, Serial No. 129,158

Term of patent 14 years

(Cl. D44—10)

To all whom it may concern:

Be it known that I, Rolf J. Falk, a citizen of the United States of America, residing at Zanesville, in the county of Muskingum and State of Ohio, have invented a new, original, and ornamental Design for a Child's Feeding Set, of which the following is a specification, reference being had to the accompanying drawings, forming a part thereof, wherein:

Fig. 1 is a perspective of a child's feeding set showing my new design; and

Fig. 1a is a section thereof on the line 1a—1a of Fig. 1.

I claim:

The ornamental design for a child's feeding set, as shown.

ROLF J. FALK.
